BUSHING AND CYLINDER REAMER

Filed Feb. 24, 1930 2 Sheets-Sheet 2

UNITED STATES PATENT OFFICE

JAMES M. DOLLY, OF CHICAGO, ILLINOIS

BUSHING AND CYLINDER REAMER

Application filed February 24, 1930. Serial No. 430,756.

This invention relates to a new and improved bushing and cylinder reamer, and more particularly to an improved appliance for truing up the cylinders in triple valves and other air-brake appliances which have become slightly worn so as to be considered defective from an air-brake standpoint.

In order to meet the rigid requirements of air-brake apparatus, it is essential that certain internal cylinders be kept uniformly true and properly centered. The object of this invention is to provide a simple, effective and easily positioned and operated tool for performing this adjustment. It will be apparent as the description proceeds that this tool is also applicable for reaming or grinding processes in other types of apparatus than the air-brake mechanism for which it is particularly designed.

Briefly described, the tool comprises a split or expandable cylindrical head adapted to substantially fit within the cylindrical opening that is to be repaired, and provided with a strip of abrasive material wrapped around the cylindrical surface of the head so as to engage the inner surface of the cylinder that is to be ground. The head is provided with internal expansion springs adapted to force the parts of the head apart so as to yieldably engage the abrasive strip with the inner surface of the cylinder. A removable retaining member is adapted to hold the parts of the head assembled before it is positioned within the valve cylinder, after which the retaining member is removed before the grinding operation takes place. A guide stem projects coaxially from one side of the head, and the stem is journaled in a two-part guide member so formed as to automatically center itself within a cylindrical passage that is coaxial with the valve cylinder. In this manner the tool is automatically held in properly centered or coaxial position within the cylinder during the grinding operation. A removable drive shaft is engageable with the opposite side of the grinding head, whereby the head may be rotated either by hand or by a motor.

The principal object of this invention is to provide an improved reamer, such as briefly

described hereinabove and disclosed more in detail in the specifications which follow.

Another object is to provide an improved form of expandable grinding head for a valve reamer.

Another object is to provide an improved form of centering guide for the reamer.

Another object is to provide an improved form of detachable retaining member for the expandable head.

Another object is to provide an improved form of detachable driving spindle for rotating the head.

Other objects and advantages of this invention will be more apparent from the following detailed description of one approved form of apparatus especially designed to carry out the principles of this invention.

In the accompanying drawings:

Fig. 1 is a central, longitudinal section through the assembled reamer in operative position within a triple valve structure.

Fig. 2 is a transverse section, taken substantially on line 2-2 of Fig. 1.

Fig. 3 is a longitudinal section through the grinding head, with the retaining member in place, the guide stem being shown in side elevation.

Fig. 4 is a perspective view of the retaining member or spring.

Fig. 5 is a transverse section, taken substantially on the line 5-5 of Fig. 3.

Fig. 6 is a perspective view of the central segment of the grinding head, with its integral guide stem.

Figs. 7 and 8 are similar perspective views of the two side segments of the grinding head.

Fig. 9 is a perspective view of the hollow cylindrical member of the guide or centering device.

Fig. 10 is a side elevation, partially broken away, of the centering nut of the guide.

This appliance may be considered as consisting of three principal parts, the reamer or grinding head, the guiding or centering means therefor, and the detachable drive shaft. The reamer comprises a multi-part cylindrical grinding head, consisting in the example here shown of a main central segment 1 and a pair of similar side segments 100.

2 and 3. The cylinder may be considered as split by a pair of substantially parallel planes spaced at equal distances at either side of the axis of the cylinder and parallel thereto. A 5 pair of guide pins 4 and 5 are formed on or positioned in the central segment 1, so as to project at opposite sides thereof perpendicular to the opposite plane surfaces of the segment, and guide openings 6 and 7 respectively are formed in the two side segments 2 and 3 to slidably engage these guide pins 4 and 5. Similar cylindrical openings 8 and 9 are formed through the two opposite similar halves of the segment 1 at either 10 side of the central axis and perpendicular to the opposite plane surfaces. Compressed expansion springs 10 are confined in these chambers 8 and 9. Preferably one of the side segments (for example the segment 3) is 15 formed with extensions 11 of these cylindrical chambers 8 and 9 so that longer springs 10 may be used. A strip of abrasive material 12, of substantially the same width as the reamer head, is positioned for use by 20 inserting one end portion 13 between the central segment 1 and the side segment 2 so that one of the springs 10 will engage this end portion 13 of the strip and hold it in place. The remainder of the strip is wrapped 25 around the cylindrical wall of the head, as best shown in Figs. 2 and 5.

It is essential that the parts of the grinding head be held in assembled relation against the action of the springs 10 before the tool 30 is positioned in the valve cylinder to be ground. For this purpose the retaining spring shown detached in Fig. 4, and in operative position in Fig. 3, is used. This retaining spring 14 comprises a pair of parallel end members 15 and 16 connected by a central portion 17 which is preferably curved or looped to one side so as to avoid engagement with the driving spindle, hereinafter described. The outer end faces of the side 40 segments 2 and 3 of the head are provided with similar openings 18 for receiving the end portions 15 and 16 of the retaining spring, as best shown in Fig. 3. It will be apparent that as long as the spring 14 is in place, the members of the head will be held 50 in assembled relation with the springs 10 compressed.

A coaxial guide stem 19 is formed integral- 55 ly with or attached to the rear end of the central head segment 1. This stem 19 is adapted to be rotatably journaled within a hollow guide cylinder 20, shown in perspective in Fig. 9 and shown in operative position in Fig. 1. One end portion of cylinder 60 20 is externally threaded at 21 to receive the internally threaded centering nut 22. The inner end of nut 22 is formed with an outwardly projecting conical surface 23, and an oppositely outwardly projecting conical 65 surface 24 is formed on an integral collar

at the end of guide cylinder 20 remote from nut 22. In the form of triple valve apparatus partially indicated in Fig. 1, a cylindrical passage in bushing 25 should be coaxial with the cylindrical chamber that is to be reamed or ground, which in this example is formed in the bushing 26 mounted in the valve structure 27. It will now be apparent that if the guide cylinder 20 is inserted through one end of bushing 25, so that the conical surface 24 engages with one end of the cylindrical passage in the bushing, and the nut 22 is screwed into position on the opposite end of cylinder 20 so that the conical surface 23 engages tightly in the opposite end of bushing 25, the guiding member will be properly centered and coaxial within the bushing 25. When the guide stem 19 is inserted rotatably within the guide cylinder 20, the grinding head will be positioned so that its cylindrical grinding surface is coaxial with the passage in bushing 25, and the cylindrical chamber in bushing 26 will then be ground in proper coaxial alignment with the passage in bushing 25.

Any suitable means may be employed for rotating the reamer or grinding tool. As here shown, the members of the grinding head are hollowed out, as indicated at 28, and from the inner end of this central chamber an internally threaded passage 29 extends coaxially through central segment 1 and into the guide stem 19. The inner threaded end 30 of a drive shaft 31 is adapted to be detachably threaded into the passage 29, as shown in Fig. 1. The opposite end portion 32 of the drive shaft or spindle is of suitable non-cylindrical form so as to be engaged by a hand wrench, or motor, or other suitable means for rotating the spindle. In case a driving motor is used, the drive spindle should have a universal joint, as indicated at 33, to compensate for the probable non-alignment of the axes of the reamer and the motor while in operation.

When this tool is to be used, the members of the grinding head, and the abrasive strip 12, are assembled, as shown in Figs. 3 and 5, and the retaining member 14 is engaged with the side segments 2 and 3 of the head so as to hold the reamer in this assembled position. The members 20 and 22 of the guide are now positioned in the passage in bushing 25. The grinding tool is now inserted in operative position by pushing the guide stem 19 into the central passage 34 in guide cylinder 20, until the grinding head is in proper position within the cylindrical chamber that is to be re-ground. The retaining spring 14 may now be removed so that the springs 10 can partially expand and force the segments of the head apart so as to yieldably engage the abrasive strip with the inner walls of the valve cylinder. The driving shaft 31 may be engaged within the grinding tool either be-

fore or after the retaining member 14 is removed, since the central loop 17 of the retaining member is so formed as to pass around the driving shaft when in place. Power is now applied to the grinding shaft 31 and the tool is rotated until the desired surface is ground within the bushing 26 or other cylindrical chamber. The tool may then be removed in an obvious manner.

It will be apparent that a new abrasive strip 12 may be very easily applied whenever necessary, and the other parts of the tool will last indefinitely.

In case the tool were to be used for grinding cylindrical chambers or valve cylinders that do not have to be symmetrical or coaxial with another passage or cylindrical opening, the guide features of this device may be omitted, and the axial length or width of the grinding face of the head depended upon to give a true cylindrical chamber for the entire depth.

While a preferred example of this improved reamer has been described in detail, it will be apparent that the specific construction of the several parts of the device can be varied in design and proportion, and some parts may be omitted, without departing from the scope of the invention as indicated by the following claims.

I claim:

1. A cylinder reamer comprising a multi-part cylindrical head, spring means confined between the parts of the head to separate the same, a retaining member having spaced parallel end portions adapted to be removably engaged with the outermost members of the head to retain the head parts in assembled relation after these parts have been pressed together against the expansive action of the spring means, and an abrasive covering surrounding the head.

2. A cylinder reamer comprising an expansible cylindrical head divided by two substantially parallel planes extending parallel to the axis of the cylinder into a main central segment and two similar side segments, parallel guide pins extending from the central segment perpendicular to the dividing planes, there being guide openings in the side segments for receiving the pins, expansion springs mounted in the central segment and engaging the two side segments for separating the same, means for rotating the cylinder, and an abrasive strip one end of which is inserted between the central segment and one side segment and clamped to one of the segments by one of the springs and the remainder of the strip wrapped around the cylindrical wall of the head.

3. A cylinder reamer comprising an expansible cylindrical head divided by two substantially parallel planes extending parallel to the axis of the cylinder into a main central segment and two similar side segments,

parallel guide pins extending from the central segment perpendicular to the dividing planes, there being guide openings in the side segments for receiving the pins, expansion springs mounted in the central segment and engaging the two side segments for separating the same, a driving spindle detachably connected with the central segment coaxially of the cylinder, and an abrasive strip wrapped around the cylindrical wall of the head.

4. A cylinder reamer comprising an expansible cylindrical head divided by two substantially parallel planes extending parallel to the axis of the cylinder into a main central segment and two similar side segments, parallel guide pins extending from the central segment perpendicular to the dividing planes, there being guide openings in the side segments for receiving the pins, expansion springs mounted in the central segment and engaging the two side segments for separating the same, means for rotating the cylinder, a retaining member detachably connected with the two side segments to hold the segments assembled against the action of the springs, and an abrasive strip wrapped around the cylindrical wall of the head.

5. A cylinder reamer comprising an expansible cylindrical head divided by two substantially parallel planes extending parallel to the axis of the cylinder into a main central segment and two similar side segments, parallel guide pins extending from the central segment perpendicular to the dividing planes, there being guide openings in the side segments for receiving the pins, expansion springs mounted in the central segment and engaging the two side segments to separate the same, a guide stem extending coaxially from one side of the central segment, a coaxial driving spindle removably engaged with the opposite side of the central segment, a retaining member detachably connected with the two side segments to hold the segments assembled against the action of the springs, and an abrasive strip wrapped around the cylindrical wall of the head.

6. A cylinder reamer comprising an expansible cylindrical head divided by two substantially parallel planes extending parallel to the axis of the cylinder into a main central segment and two similar side segments, parallel guide pins extending from the central segment perpendicular to the dividing planes, there being guide openings in the side segments for receiving the pins, expansion springs mounted in the central segment and engaging the two side segments to separate the same, a guide stem extending coaxially from one side of the central segment, a guide member consisting of a hollow cylinder in which the stem is journaled and a nut threaded on one end portion of the cylinder, there being an outwardly extending conical

surface on the inner end of the nut and an opposed outwardly extending conical surface on the other end of the cylinder, whereby the guide member may be coaxially centered 5 within a cylindrical passage, a coaxial driving spindle removably engaged with the opposite side of the central segment of the head, a detachable retaining member connecting the two side segments to hold the segments 10 assembled against the action of the springs, and an abrasive strip wrapped around the cylindrical wall of the head.

7. A cylinder reamer comprising an expansible cylindrical head divided by two substantially parallel planes extending parallel 15 to the axis of the cylinder into a main central segment and two similar side segments, parallel guide pins extending from the central segment perpendicular to the dividing 20 planes, there being guide openings in the side segments for receiving the pins, expansion springs mounted in the central segment and engaging the two side segments to separate the same, a guide stem extending coaxially from one side of the central segment, 25 there being a threaded opening formed coaxially in the side of the central segment of the head opposite the guide stem, a driving spindle having a threaded end portion adapted 30 to be detachably engaged in the opening, a retaining member detachably connected with the two side segments to hold the segments assembled against the expansive action 35 of the springs, and an abrasive strip wrapped around the cylindrical wall of the head.

8. A cylinder reamer comprising an expansible cylindrical head divided by two substantially parallel planes extending parallel to the axis of the cylinder into a main central segment and two similar side segments, 40 parallel guide pins extending from the central segment perpendicular to the dividing planes, there being guide openings in the side segments for receiving the pins, expansion springs mounted in the central segment and engaging the two side segments to separate the same, a guide stem extending coaxially from one side of the central segment, 45 a guide member consisting of a hollow cylinder in which the stem is journaled and a nut threaded on one end portion of the cylinder, there being an outwardly extending conical surface on the inner end of the nut and an opposed outwardly extending conical surface 50 on the other end of the cylinder, whereby the guide member may be coaxially centered within a cylindrical passage, there being a threaded opening formed coaxially in the side of the central segment of the head 55 opposite the guide stem, a driving spindle having a threaded end portion adapted to be detachably engaged in the opening, a retaining member detachably connected with the two side segments to hold the segments assembled 60 against the expansive action of the 65

springs, and an abrasive strip wrapped around the cylindrical wall of the head.

9. A cylinder reamer comprising an expansible cylindrical head divided into a plurality of segments, springs confined between the segments to separate same, and an expansible strip having one end inserted between two of the segments and clamped to the segment by one of the springs, the remainder of the strip being wrapped around the cylindrical wall of the assembled segments. 70

10. A cylinder reamer comprising an expansible cylindrical head divided into a plurality of segments, springs confined between the segments to separate same, and an expansible strip having one end inserted between two of the segments and secured to one of the segments, the remainder of the strip being wrapped loosely around the cylindrical wall of the assembled segments. 75
